TRUSS PAD

Benjamin F. Pease, Wyoming, Ohio

Application March 6, 1931, Serial No. 520,520

7 Claims. (Cl. 128—116)

My invention relates to supporting constructions for parts of the human body, and particularly to truss pads and similar structures.

In the art there has been considerable development in the provision of adjustable pads for trusses, the object being to provide more or less standard apparatus suited for adjustment to the body of the particular person wearing the truss, so that the pad may be arranged to exert the pressure in the particular position where the hernia exists. Pads have been made of different materials, in some instances having a surface covering of leather, and in other instances being covered with softer material, such as sponge rubber. Further, some pads have been provided with spherical knobs or protuberances adapted to exert localized pressure upon one particular spot, with the main body of the pad exerting some pressure on the area of the body surrounding the particular spot.

Adjustability of the position of the pad does not amount to complete adjustability for the reason that the shape of the pad is of equal, if not greater importance in adapting it to the particular needs of a given wearer. Adequate support cannot be obtained by correct positioning of the pad combined with a desired degree of pressure. By way of example, in umbilical hernia, the abdomen of the wearer may be covered with a layer of fatty tissue of more or less thickness. When a pad has been correctly positioned, an increase of pressure will result merely in an uncomfortable and even injurious compression of the fatty tissue without affording proper support, unless the pad have a portion adapted to penetrate the fatty tissue and afford support at the place and over the area desired. It is a fact that the average hernia, if put back into place, may be held in place by pressure over an area no larger than the ends of two fingers. In order that it may be held in place to the best advantage, a similarly localized pressure should be exerted thereon continuously. A general pressure over a much more extended area will not serve exactly the same function no matter how intense. On the other hand, means for exerting only the local pressure, as the sole pad of a truss or the like, would not be entirely satisfactory for the reason that it would not be backed up by a supporting surface and its penetration could not be controlled. It will be obvious that the shape of the pad surface and the depth and configuration of projecting portions thereof are subject to such wide and innumerable variations in adapting them to the needs of individual wearers, that it is not possible

with a reasonable number of standard forms, to fit exactly the needs even of a considerable percentage of wearers.

An object of my invention therefore, is the provision of an adjustable pad which can be exactly varied in the shape and the configuration of the supporting surfaces, to adapt it to the needs of an individual wearer.

It is another object of my invention to provide a pad in which a bearing or supporting surface 10 may be adjusted with respect to the main surface of the pad, so as to be extended therefrom more or less as required in an individual case.

Still another object of my invention is the provision, in a truss or other supporting device, of 15 means in connection with positioning and pressure means, for varying the conformation of the pad.

These and other objects of my invention which will be set forth hereinafter, or will be apparent 20 to one skilled in the art upon reading these specifications, I accomplish by that certain combination and arrangement of parts of which I have shown a preferred embodiment.

Referring to the drawing:

Figure 1 is a rear elevation of a truss pad showing one type of adjustable mounting.

Figure 2 is a sectional view taken along the lines 2—2 in Figure 1.

Figure 3 is a detail rear elevation of the pad 30 with parts broken away.

Figure 4 is a side elevation of the cup-shaped member which varies the bottom of the protuberance.

Figure 5 is a side elevation of the washer which 35 bears against the member shown in Figure 4.

The pad may in this instance have a bearing surface composed of a sheet of sponge rubber 1, secured to a disc 2, preferably of leather, having the same shape as the rubber sheet. A lacing 40 strip 3, as indicated, may be employed to secure the sheet of sponge rubber to the disc 2.

I have merely shown one type of pad in order to illustrate the type of apparatus to which my invention relates, it being within the scope of 45 my improvements to utilize the principle of other types of pads.

Against the inner surface of the cover 1, I mount an annular member 4, provided with threaded holes 5, and I preferably secure the 50 member 4 in position by means of an annular piece 6, which is cemented or vulcanized, or otherwise attached to the inner surface of the pad 1.

Bearing against the inner surface of the pad 55

1, I have shown a resilient cup-shaped member 1, and against the inner surface of the cup-shaped member 1 there is a follower washer 8.

5 A plate 9 is secured in position bearing against the outer surface of the disc 2. The plate 9 is secured in position by means of screws 10, which pass through threaded apertures in the plate 9, and seat in the threaded openings 5 in the annular member 4.

10 An arm 11 is secured against the plate 9 with threaded studs 12, which engage nuts 13 retained against the inner surface of the plate 9.

15 A screw 14, having an enlarged end 15, bears against the plate 8 which, in turn, bears against the cup-shaped member 1, and as the screw 14 is turned down a protuberance is extended out to a desired degree of contour.

20 In the construction which I have illustrated, a threaded nut 16 is welded adjacent an opening in the plate 9 to mount and secure the threads of the screw 14.

The arm 11 illustrated, has slots 17 which provide clearance for the threaded studs 12.

25 The arm 11 is shown as secured to a strap 18, which ordinarily passes around the body and so adjusts the pad at a desired location.

30 While the construction which I have described illustrates one modification of my invention, it will be apparent that other shapes of pads and other adjustable means by which the protuberance of the pad may be varied as to contour, may be provided. The principle of the invention being new, to the best of my knowledge and belief, I claim the same broadly herein.

35 Having thus described my invention, what I claim as new and desire to secure by Letters Patent is:—

40 1. In a truss pad, a rigid base, an integral body of relatively soft sponge rubber, having its major portion secured to said base leaving a small portion of said body free of said base; a button interposed between said base and said free portion of said body and means to move said button from said base to distend said free portion of said body to produce a bulge adjacent said free body portion independently of said major portion.

45 2. In a pad, a support, an integral body of sponge rubber, and a backing member therefor, said body having a forward face, means securing the major portion of the rear face thereof to said support and means in back of the body on the support to exert an outward pressure on a relatively small portion only of said body to form a

bulge on said forward face while the main marginal area of said face is held by said support in substantially its normal condition.

3. In a pad, a thick integral body of relatively soft, elastic material having a forward face 5 adapted to bear against a portion of a human body, a support secured to means holding a relatively wide marginal portion of said body whereby the marginal portion is in its normal condition and means on said support to exert an outward pressure on a more central portion of said body to distend said portion only thereof, to thereby form a bulge on a relatively small central area of said face.

4. In a truss pad, a thick integral body of soft 15 elastic material having a bearing face, means to hold the main portion of said body against distortion and means to adjustably distend the remaining portion only of said body to form a bulge of limited area on said bearing face which 20 protrudes from the main bearing face of the pad.

5. A pad composed of an integral body of thick elastic material and a support therefor, said pad having an outer bearing face and means in back of the body on said support to bulge a minor 25 portion only thereof outwardly and cause the same to protrude from the remainder of the bearing face, means to hold the major portion of the body against distortion, said bulging means being adjustable to regulate the extent of said 30 bulge.

6. In a pad of the character described, a thick body contacting cushion of sponge rubber and a support therefor, means to hold a substantial marginal portion of said cushion to said support 35 in order to prevent distortion, means on said support to exert an outward pressure on the remaining unitary portion only of said cushion to reform a bulge on the forward face thereof while a substantial marginal portion of the surface of 40 said forward face is held by the support substantially in its normal condition.

7. In a truss pad, a rigid base, a main body of relatively soft sponge rubber, the major area of the rear face of said body secured to said base 45 leaving a small area of said rear face free of said base and means to exert an outward pressure on said free area to distend a minor portion of said body and cause a minor portion of the forward face of the pad to bulge outwardly independently 50 of the contour of the major portion of said forward face.
